UNITED STATES PATENT OFFICE.

JOHN M. HOTHERSALL, OF BROOKLYN, NEW YORK, ASSIGNOR TO AMERICAN CAN COMPANY, OF NEW YORK, N. Y., A CORPORATION OF NEW JERSEY.

APPARATUS FOR APPLYING CAN CLOSURES.

Application filed June 14, 1920. Serial No. 388,780.

To all whom it may concern:

Be it known that I, JOHN M. HOTHERSALL, a citizen of the United States, residing in Brooklyn, in the county of Kings and State of New York, have invented a new and useful Improvement in Apparatus for Applying Can Closures, of which the following is a specification.

This invention relates in general to devices for applying can closures and has more particular reference to the provision of means for applying closures to the nozzles of cans, where the nozzles have been previously positioned upon the can bodies, although it will be manifest as the invention is better understood that it has other and more general application.

The invention is of especial value in the closing of nozzles on large cans of the character hereinbefore employed for containing varnish and the like wherein a frangible disc of metal or other material is seated over the nozzle opening and seamed in suitable fashion with the upper open nozzle end. Prior to my present invention it has been usually the custom in sealing such nozzles with this form of closure to perform the operation with a hand crimper or other tool which operation is a tedious one where the output is large, and results in the formation of nozzles of varying tightness and quality of sealing. Moreover, it frequently deforms the nozzle and renders the can unsightly.

The principal object of my present invention is the provision of means quickly and easily operable to apply closures to the nozzles of relatively large cans of this and other character.

Another important object of the invention is the provision of means for producing nozzles of uniform satisfactory quality and pleasing appearance.

A further object of the invention is the provision of an apparatus of the character described consisting of few and simple parts requiring little or no adjustment and unlikely to require frequent repair or replacement.

Numerous other objects and advantages of the invention will be apparent as the invention is better understood from the following description which taken in connec-

tion with the accompanying drawing illustrates a preferred embodiment thereof: 55

Referring to the drawing:

Figure 1 is a side elevation of an apparatus embodying my present invention;

Figure 2 is a front view thereof;

Figure 3 is a partial enlarged view in plan, partly in section, showing the arrangement of the passive die;

Figure 4 is a section taken vertically through the same;

Figure 5 and 6 are sections through the nozzle showing the operation.

The apparatus shown on the drawing for the purpose of illustrating the present preferred embodiment of my inventive idea comprises a die press in general of any preferred form or construction, detailed description of which is not believed necessary. It may be stated, however, that this press includes a frame 11, a bed 12, a pulley 13 on the crank shaft 14, and the die slide 15. 70 An operating treadle or lever 16 is provided to cause the shaft 14 to be operatively connected with the pulley and the press operation to result, all in the usual manner.

The cam selected for the purpose of illustration is of the rectangular variety and is indicated on the drawing by reference character 17. A nozzle 18 is located in the present instance adjacent a corner of the can and is provided with an outstanding shoulder 19 and an upwardly extending flange 21 at its top. This shoulder and flange are provided by offsetting the material of the nozzle near the end and at the shoulder 19 as may be seen in Figure 5. The closure 20

comprises a sheet of metal 22 coated with a suitable hermetic sealing material 23, which is preferably a sheet of paper. The sheets 22 and 23 are formed up into short cylindrical marginal flanges 24, all as may be 95 seen from figure 5. The closing with a hermetic seal is performed by curling the flange 21 over and down within the flanges 24 of the closure as indicated at 25 in Figure 6. This nozzle and closing means are 100 new and form the subject matter of a co-pending application Serial No. 388,779, filed by me on June 14, 1920.

The nozzle 18 is positioned on the can prior to the application of the closure and 105 is fixed in place in any suitable or preferred

2 manner, the showing on Figure 4 in this respect being merely schematic.

The cans are filled with their content and the closure loosely laid in place and are 5 then die-closed by the apparatus of the drawing. The closing instrumentalities comprise a passive die arrangeable beneath the shoulder 19 and an active die mounted in the die-carrier slide which descending 10 presses inwardly the flange 21 and bends it in the manner shown in Figure 6, at a single operation, the while co-operating with the passive die so that uniformity of hermetic seal results.

15 The passive die in the present instance comprises two movable jaws 26, pivoted at 27, upon an auxiliary housing 28, mounted on the press table. This housing has an angular pocket 29 into which a vertical corner of the can body may be thrust. The die jaws have arcuate adjacent ends 31 provided with semi-circular or semi-conical pockets 32 adapted to embrace the nozzles when the dies have been swung to the normal 20 position shown in Figure 3. Assuming the parts to be arranged as shown in this figure, the jaws tightly embrace the nozzle having an upstanding circular wall 33 engaging beneath the shoulder 19 to support 25 it against the closing action. The active die is indicated by reference character 34 and has a closing recess 35 tapered on its outer side to first bend the flange 21 inwardly, the taper continuing to a curve at the top 30 to curl it down over the flange 24. This is the action when the active die descends and constitutes the entire closing operation in the present instance. Thereafter, the active die ascends and the can is pulled from 35 place, swinging the jaws 26 to an open position by reason of the outward movement of the nozzle. The next succeeding can is then merely pushed into place, its nozzle engaging the jaws 26 and moving them to the closed position for a subsequent operation. Each jaw 26 has a tail 36 movable beneath a guide plate 37 fixed by bolts 38 upon an upstanding curved wall 39 at the housing, these guide plates serving also to restrain 40 tilting of the die jaws in the closing operation.

Means are provided for preventing operation of the active die except when the passive dies are in normal position. This 45 means in the present instance consists of a rod 41 slidably mounted in bearings in the guide 37 at the right of Figure 3, in the housing and in the bed of the press, said bearings being indicated by reference characters 42, 43 and 44. This rod when in normal position is arranged with a reduced part 45 in registration with the path of travel of a tail 36 of the right hand jaw. It is, however, adapted to be lowered when 50 the treadle 26 is pressed to dispose an upper

part 50 of larger diameter at this path of travel and across it. The location of the rod 41 is such, as may be observed by viewing Figure 3, that rod movement from normal position, can only occur when the dies are in normal position, i. e., embracing a can nozzle. The rod 41 is connected to an arm 45 on a shaft 46 having bearings at 47 in the press ring. The shaft 46 in turn has a second arm 48 connected by rod 49 with the lever or treadle 16. As has been stated this treadle must be depressed to produce descent of the active die 34 so that the enlarged part 50 of the rod 41 prevents this operation except when the jaws are in normal position, because otherwise the part 50 will rest on the top of the jaw and prevent any descent of the rod 41. For the coupling of the rod 41 with the clutch so that they may have the related operation above described, any well known and suitable mechanism may be employed. I have illustrated in Figs. 1 and 2 a rod 51 which connects the treadle 16 with a clutch shifting lever 52 which controls the movable element 53 of the clutch. The latter acts in a known manner to connect and disconnect the power wheel 13 with the press-shaft 14.

It is thought that the invention and many of its attendant advantages will be understood from the foregoing without further description and it will be manifest that various changes may be made in the form, construction and arrangement of the parts without departing from the spirit and scope of the invention, or sacrificing all of its material advantages the form hereinbefore described being merely a preferred embodiment.

105 I claim:

1. In an apparatus for applying can closures, the combination of a reciprocating die and an oscillating die, said oscillating die being moved into operative relation with said reciprocating die by movement of the can to the operating station, said reciprocating die being formed with a depending margin from which the wall of the die extends upward and thence inward and thence downward to produce a curling groove.

110 2. In an apparatus for applying can closures, the combination of a reciprocating die and an oscillating die, said oscillating die being moved into operative position by movement of the can into operative position, said reciprocating die being formed with a depending margin from which the wall of the die extends upward and thence inward and thence downward to produce a curling groove.

115 3. In an apparatus for applying can closures, the combination of a reciprocating die and a passive die, said passive die being movable into operative relation with the reciprocating die by movement of the can to

operative position, said reciprocating die being formed with a depending margin from which the wall of the die extends upward and thence inward and thence downward to 5 produce a curling groove.

4. In an apparatus for applying can closures, the combination of an active die and a passive die, said passive die being moved into position embracing the part of the can 10 to be acted upon by movement of the can into operative position, said active die being formed with a depending margin from which the wall of the die extends upward and thence inward and thence downward to 15 produce a curling groove.

5. In an apparatus for applying can closures, the combination of an active die and a passive die, said passive die comprising pivotally mounted jaws swung into and out 20 of operative position by movement of the can toward and from the operating station, said active die being formed with a depending margin from which the wall of the die extends upward and thence inward and 25 thence downward to produce a curling groove.

6. In an apparatus for applying can closures, the combination of an active die and a passive die, said passive die being brought 30 to operative position by movement of the can body and means for preventing movement of the active die except when the passive die is in operative position, said active die being formed with a depending margin from 35 which the wall of the die extends upward and thence inward and thence downward to produce a curling groove.

7. In an apparatus for applying can closures, the combination of a passive die 40 adapted to embrace a can nozzle and protruding over the can body provided with said nozzle and an active die co-operating with said passive die for securing a closure on said nozzle, said active die being formed 45 with a depending margin from which the wall of the die extends upward and thence inward and thence downward to produce a curling groove.

8. In an apparatus for applying can closures, the combination of a passive die 50 adapted to embrace a can nozzle and protruding over the can body provided with said nozzle and an active die co-operating with said passive die for securing a closure 55 on said nozzle, said passive die being movable to permit removal of the can body from the apparatus, said active die being formed with a depending margin from which the wall of the die extends upward and thence 60 inward and thence downward to produce a curling groove.

9. In an apparatus for applying can closures, the combination of a passive die comprising a pair of movable jaws adapted to 65 embrace a nozzle on a can body, an active

die for securing a closure to said nozzle, said active die being formed with a depending margin from which the wall of the die extends upward and thence inward and thence downward to produce a curling groove. 70

10. In an apparatus for applying can closures, the combination of a passive die comprising a pair of movable jaws adapted to embrace a nozzle on a can body, an active die for securing a closure to said nozzle and 75 means for preventing operation of the active die except when said jaws are in operative position.

11. In an apparatus for applying can closures, the combination of a passive die comprising a pair of movable jaws adapted to embrace a nozzle on a can body, an active die for securing a closure to said nozzle, said jaws being movable into nozzle embracing position by movement of the can body to the 80 nozzle closing station, said active die being formed with a depending margin from which the wall of the die extends upward and thence inward and thence downward to produce a curling groove. 85

12. In an apparatus for applying can closures, the combination of a pair of pivotally mounted jaws constituting a passive die and movable to nozzle embracing position when the can body is moved into nozzle closing position, and an active die movable down to compress the edge of the nozzle about a nozzle closure and against the passive die formed by said jaws, said active die being formed with a depending margin from 90 which the wall of the die extends upward and thence inward and thence downward to produce a curling groove. 95

13. The combination of a die press, a pair of pivotally mounted jaws therein forming 105 a passive die, an active die therein, and means for preventing starting of the press to produce actuation of the active die except when said jaws are in operative position.

14. The combination of a die press, a pair 110 of pivotally mounted jaws therein forming a passive die, an active die therein, a control lever for producing actuation of the active die, and means connected with the control lever and projectable across the path of 115 travel of said jaws and movable only when said jaws are in operative position.

15. The combination of a die press, active and passive dies therein, one of said dies having a movable part to permit insertion 120 and withdrawal of the can to be operated upon, a control lever movable to produce actuation of the active die, and means associated with said control lever and projectable across the path of travel of said movable die 125 part only when said movable die part is in operative position, whereby said active die is rendered inoperable except when said die part is in operative position.

JOHN M. HOTHERSALL.
